UNITED STATES PATENT OFFICE.

GILBERT SAMUELSON, OF SANDPOINT, IDAHO, ASSIGNOR OF ONE-HALF
TO EDWARD McGREGOR, OF SANDPOINT, IDAHO.

CURRENT-MOTOR.

SPECIFICATION forming part of Letters Patent No. 779,320, dated January 3, 1905.

Application filed March 26, 1904. Serial No. 200,113.

To all whom it may concern:

Be it known that I, GILBERT SAMUELSON, a citizen of the United States, and a resident of Sandpoint, in the county of Kootenai and State 5 of Idaho, have invented a new and Improved Current-Motor, of which the following is a full, clear, and exact description.

This invention relates to improvements in motors designed to be placed in a river or 10 other body of water in which there is a current, the object being to provide a current-motor of simple and novel construction that may be utilized for pumping water for irrigating purposes and may be also utilized for 15 operating machinery.

I will describe a current-motor embodying my invention and then point out the novel features in the appended claims.

Reference is to be had to the accompanying 20 drawings, forming a part of this specification, in which similar characters of reference indicate corresponding parts in all the figures.

Figure 1 is a side elevation of a current-motor embodying my invention. Fig. 2 is a plan 25 view thereof. Fig. 3 is a plan view, partly in section. Fig. 4 is a transverse section, and Fig. 5 is a section on the line 5 5 of Fig. 3.

The motor comprises a hull or boat 10, supported on which is a deck 11, the said deck 30 being connected to the hull, as here shown, by means of posts 12. Arranged to rotate independently on a shaft 13 at the stern of the vessel are drums 14 15, from which the anchor-cables 16 17 extend. The inner or adjacent faces of the drums are provided with gear-wheels 18, with either one of which a pinion 19 on a shaft 20 may be engaged. This shaft 20 is arranged to slide in its bearings, and it is provided with a crank-handle 21. By 35 this arrangement it is obvious that either one of the drums may be operated without imparting motion to the other drum.

The cables extend around pulleys 22, arranged at the stern underneath the flooring 45 23, and from these pulleys 22 the cables pass around pulleys 24 at the bow of the boat and thence upward through the flooring and out through openings in the bow, and these cables of course are connected to suitable anchors.

Anchoring-cables 25 also extend from the 50 drums through the stern of the vessel.

Mounted to swing on an upright 26 is a pawl 27, designed to engage with the two gears 18, so as to hold the drums from rotary motion. It is designed, however, that this pawl shall 55 release the gears when the water rises, therefore permitting more cable to be paid out. On the rearwardly-extended end of the pawl is a downwardly-extended rod 28, and preferably this rod is made adjustable with relation to the pawl, and on the lower end of the rod is a float 29. Should the tide rise, the boat being held down by the anchors, the water will force the float 29 upward, consequently releasing the pawl from the gear-wheels, permitting the cables to run freely 60 until the boat rises to its normal position. The stern anchors will prevent the stern of the boat from floating upward, or, in other words, the bow and stern anchors will hold 70 the boat on a practically even keel.

At the front or bow of the boat and extended transversely thereof is a water-wheel 30, mounted on a shaft 31, which passes through a bearing-box 32, arranged in the 75 stern of the boat. Loosely mounted on the shaft 31 is a sprocket-wheel 33, from which a chain 34 passes upward through the deck 11 and engages with a sprocket-wheel 35 on a power-shaft 36. On the sprocket-wheel 33 is 80 a clutch member 37, designed to be engaged by a clutch member 38, mounted to move longitudinally on the shaft 31 and rotating therewith. The clutch member 38 has an annular channel in which fingers on a yoke 39 engage. 85 This yoke is attached to a shifting lever 40, mounted in an arm 41. By this arrangement the wheel 30 may be placed in or out of operation. It may be here stated that this wheel will be operated by cross-currents that may 90 occur and assist other wheels driven by the direct current and to be hereinafter described.

At its rear end the power-shaft 36 is connected to a bevel-pinion 42, which engages with a bevel-pinion 43, loosely mounted on a 95 counter-shaft 44. Movable longitudinally on the shaft 44 and rotating therewith is a clutch member 45, designed for engagement with a

clutch member 46 on the pinion 43, so as to cause said pinion to rotate with the shaft when desired. This clutch-section 45 is shifted by means of a lever 47. Connected to the shaft 5 44 is a sprocket-wheel 48, from which a chain 49 passes to a pinion 50 on the shaft of an electric generator 51, mounted on the deck 11 and from which wires extend to the shore for electric-lighting or other purposes.

10 Having bearings in opposite sides of the boat are tubular shafts 52 53, on which water-wheels 54 55 are mounted. These wheels are designed to be operated by the direct current of the stream. On these tubular shafts are 15 sprocket-wheels 56, from which chains 57 extend to sprocket-pinions 58 on the counter-shaft 44. Extended loosely into the tubular shafts is a crank-shaft 59, having two cranks 60 61. On the inner end of the tubular shaft 20 52 are clutch-teeth designed to be engaged by a clutch member 62, mounted to slide on the crank-shaft, but designed to rotate therewith, and rigidly attached to the crank-shaft at the side of the tubular shaft 53 is a clutch member 63, designed to be engaged by a clutch member 64, mounted to slide on the tubular shaft 53 and to rotate therewith. The clutch member 62 is engaged by a shifting arm 65, attached to a shaft 66, which extends upward 25 through the deck 11, and the clutch member 64 is engaged by a shifting arm 67, attached to a shaft 68, which also extends upward through the deck 11.

Extended from the upper end of the shaft 30 66 is an arm 69, from which a link 70 extends to a connection with a disk 71, mounted to rotate on the deck. Attached to the upper end of the shaft 68 is an arm 72, which has a link connection 73 with the said disk 71. It 35 will be noted that the links 70 and 73 connect with the disk at opposite sides of the disk-pivot. Attached to the disk is a turning-lever 74, on which is a spring-pressed lever 75, carrying a rod 76, which extends down through an opening in the disk and is 40 designed to engage in any one of a series of holes formed in the deck, so as to hold the sliding clutch members in or out of engagement with their adjacent members. Obviously by rotating the disk the clutch member 45 62 will be moved inward, or toward the center of the boat, while the clutch member 64 will be moved outward. By the arrangement of clutches the bow wheel and the side wheels 50 55 may be caused to operate all together, or the bow wheel may be thrown out of gear, leaving the two side wheels to operate, or the side wheels may be thrown out of gear, permitting the bow wheel to operate alone.

60 On the driving-shaft 36 I have shown a sprocket-wheel 77, from which a chain may pass to drive machinery on shore.

Arranged in the forward portion of the boat are four pumps 78 79 80 81, and at the rear 65 portion of the boat are four pumps 82 83 84

85. These pumps are connected to tubes which extend through the bottom of the boat, and in the lower part of each pump-cylinder is an upwardly-opening valve 86, and operating in each pump-cylinder is a piston 87. From the 70 pistons in the pump-cylinders 80 and 81 piston-rods 88 extend upward and connect with arms 89. Extended forward from a rock-shaft 90, mounted in hangers 91, attached to the under side of the deck 11, and from arms 92, projected rearward from the rock-shaft, rods 93 extend downward and connect with the pistons in the pumps 78 79. The pistons in the pump-cylinders 82 83 have connections 94 with arms 95, extended rearward from a rock-shaft 96, 80 mounted in hangers 97, and the pistons in the pump-cylinders 84 85 are connected to forwardly-extended arms 98 by means of rods 99.

A connecting-rod 100 is attached at one end to an arm 101, connected to the rock-shaft 96, 85 and the opposite end of this rod 100 engages with the crank 60, and from the crank 61 a connecting-rod 102 leads forward and has pivotal connection with an arm 103, attached to the rock-shaft 90.

The several pumps are connected by 90 branches with a pipe 104, which extends along the bottom or flooring of the boat, and from the rear end of this pipe 104 a pipe 105 leads upward through the deck 11 and has oppositely-extended branches 106, with either one of which a hose or the like may be attached, depending upon the direction or to which bank it is desired to carry the water. In each branch 106 is a valve 107.

The operation of the device is quite clear—that is, it is obvious that as the current rotates the side wheels the crank-shaft will be operated, consequently operating the pistons in the pump-cylinders. The upward movement of 105 the pistons will draw the water in, while the downward movement will force the water out through the discharge-pipe.

Having thus described my invention, I claim as new and desire to secure by Letters Patent— 110

1. A current-motor comprising a boat, current-operated devices carried by the boat, anchoring devices, and means for automatically releasing the anchoring devices permitting the boat to rise.

2. A current-motor comprising a boat, water-wheels carried by the boat, devices adapted to be operated by the water-wheels, winding-drums arranged in the boat, anchor-cables extended from said drums, the said drums being mounted to rotate independently one of another, gear-wheels on the inner or adjacent faces of said drums, a pawl mounted to swing and to engage with the gear-wheels of both drums, and a float carried by the rearwardly- 120 extended end of the pawl.

3. A current-motor comprising a boat, current-operated devices carried by the boat, cable-winding drums carried by the boat, a winding mechanism common to both the 125 130

drums, and means actuating by rising water to release the drums to permit the paying off of anchoring-cables.

4. A current-motor comprising a boat, water-wheels arranged at opposite sides thereof, tubular shafts on which the wheels are mounted, the said tubular shafts having bearings in the sides of the boat, a crank-shaft extended loosely into said tubular shafts, clutch mechanism for causing the crank-shaft to rotate with the tubular shafts and pumps in the boat operated by said crank-shaft.

5. A current-motor comprising a boat, water-wheels on opposite sides thereof, tubular shafts to which the wheels are attached, said tubular shafts having bearings in the sides of the boat, a crank-shaft extended loosely into said tubular shafts, clutches for connecting the crank-shaft operatively with the tubular shafts, the said clutches comprising sections movable lengthwise on the shaft, shafts extended vertically in the boat, shifting arms connecting the lower portions of said shafts with the sliding clutch-sections, a deck on the boat through which the vertical shafts extend, arms on the upper ends of said vertical shafts, a disk mounted to rotate on the deck, link connections between said arms and the disk, a lever for turning the disk, and means for holding the disk as adjusted.

6. A current-motor comprising a boat, a pair of independently-rotating drums carried by the boat, gear-wheels on the adjacent ends

of the drums, a winding-pinion movable for engagement with either one of said gear-wheels, a pawl adapted to engage with said gear-wheels, and a water-actuated float attached to said pawl.

7. A current-motor comprising a boat, a deck supported above the same, a power-shaft mounted on the deck and extended lengthwise thereof, a water-wheel in front of the boat and having driving connection with said power-shaft, a counter-shaft, water-wheels on opposite sides of the boat and having driving connection with said counter-shaft, a bevel-gear on the power-shaft, a bevel-gear loosely mounted on the counter-shaft and engaging with the first-named gear, a clutch member carried by said loose gear, a clutch member mounted to slide on the counter-shaft but to rotate therewith, means for shifting the movable clutch-section into and out of gear with the clutch of the gear-wheel, a sprocket-wheel carried by the counter-shaft, and an electric generator mounted on the deck and operated from said sprocket-wheel.

In testimony whereof I have signed my name to this specification in the presence of two subscribing witnesses.

GILBERT SAMUELSON.
